(57) **CLAIM**

The ornamental design for a place setting overlay for a table, as shown and described.

DESCRIPTION

FIG. 1 is a perspective view showing a first embodiment of a place setting overlay for a table, in condition of use;

FIG. 2 is a perspective view thereof, illustrated in a flat configuration;

FIG. 3 is a top plan view of FIG. 2, the bottom plan view being a mirror image thereof;

FIG. 4 is a front elevational view of FIG. 2, the rear elevational view being a mirror image thereof;

FIG. 5 is a left-side elevational view of FIG. 2, the right-side elevational view being a mirror image thereof;

FIG. 6 is a perspective view showing a second embodiment of a place setting overlay for a table, in condition of use;

FIG. 7 is a perspective view thereof, illustrated in the flat configuration;

FIG. 8 is a top plan view of FIG. 7, the bottom plan view being a mirror image thereof;

FIG. 9 is a front elevational view of FIG. 7, the rear elevational view being a mirror image thereof; and,

FIG. 10 is a left-side elevational view of FIG. 7, the right-side elevational view being a mirror image thereof.

The broken lines showing a table in FIGS. 1 and 6 depict environmental matter and form no part of the claimed design. The dot-dash type broken lines represents a boundary of the claimed design, and the remaining broken lines represent portions of the design outside of the boundary that form no part of the claimed design.
